J. HUBER.

METALLIC FENCE POST.

APPLICATION FILED APR. 1, 1910.

Patented Mar. 26, 1912.

UNITED STATES PATENT OFFICE.

JOSEPH HUBER, OF ELMA, IOWA.

METALLIC FENCE-POST.

1,021,409.

Specification of Letters Patent. Patented Mar. 26, 1912.

Application filed April 1, 1910. Serial No. 552,909.

To all whom it may concern:

Be it known that I, JOSEPH HUBER, citizen of the United States, residing at Elma, in the county of Howard and State of Iowa, 5 have invented certain new and useful Improvements in Metallic Fence-Posts, of which the following is a specification.

This invention relates to fence posts and has for its object the provision of a metallic 10 post of simple and durable construction, which will effectually withstand both longitudinal and lateral strains incident to the stretching of line wires.

A further object is to provide a fence post 15 having spaced seating recesses formed therein for the reception of the line wires, said line wires being held against accidental displacement by a removable locking rod intersecting the wire receiving recesses.

20 A further object is to provide the post with a cap adapted to bear against the adjacent end of the locking rod and retain the latter to its seat.

A further object is to reinforce and 25 strengthen the post by the provision of a metal plate extending the entire height of the post and having recesses formed therein and registering with the wire receiving recesses, thereby to permit the passage of the 30 locking rod.

A still further object of the invention is generally to improve this class of devices, so as to increase their utility, durability and efficiency.

35 Further objects and advantages will appear in the following description, it being understood that various changes in form, proportions and minor details of construction may be resorted to within the scope of 40 the appended claims.

For a full understanding of the invention and the merits thereof, reference is to be had to the following description and accompanying drawings, in which:

45 Figure 1 is a perspective view of a metallic post constructed in accordance with my invention; Fig. 2 is a longitudinal sectional view of the same; Fig. 3 is a perspective view of the casing sections, one of said sections being broken away; Fig. 4 is a perspective view of a portion of the reinforcing plate; Fig. 5 is a transverse sectional view taken on the line 5—5 of Fig. 2; Fig. 6 is a transverse sectional view taken on the line 55 6—6 of Fig. 2.

Corresponding and like parts are referred to in the following description and indicated in all the views of the drawings by the same reference characters.

The fence post comprises a hollow body portion or casing preferably formed in two sections 5 and 6 having their adjacent longitudinal edges overlapped and rigidly united by bolts or similar fastening devices 7. The metal constituting the sections 5 and 6 is 60 pressed or bent laterally to produce oppositely disposed reinforcing ribs 8 preferably arranged at right angles to the vertical plane of the post and gradually increasing in thickness from a point adjacent the top of the casing to the lower end thereof, as shown.

One longitudinal edge of the body portion or casing is formed with a plurality of spaced seating recesses 9 adapted to receive the line wires 10, thus to maintain said line 75 wires in proper spaced relation. Disposed within the hollow body portion, is a reinforcing plate 11 preferably extending the entire height of the post and secured in position by the bolts or fastening devices 7.

One longitudinal edge of the reinforcing plate 11 is cut-away to produce spaced recesses 12 which register with the seating recesses 9 so as to accommodate the line wires, the metal between the recesses 12 being concave transversely to form a seat 13 for the reception of a locking rod 14. The locking rod 14 is preferably formed from a single length of wire having one end thereof bent to produce a downwardly extending hook 15 adapted to enter a seating recess 16 formed in the upper edge of the body portion or casing, thus to prevent rotation of the locking rod in its seat. The locking rod 14 intersects the wire receiving recesses 9 and is disposed in advance of the line wires 10 so as to retain the line wires in position on the post.

The upper end of the reinforcing plate is projected vertically beyond the casing or body portion to form an extension 17 for the reception of a removable cap 18, there being registering openings 19 formed in said cap and extension 17 to permit the insertion of a cotter pin or similar fastening device 20. One side of the cap 18 is cut-away to form a recess or seat 21 for the hooked end of the locking rod 14, the length of the cap 18 being such as to overlap the top of the body portion or casing and entirely 11

house the hook 15 when the cap is in position on the post, as best shown in Fig. 1 of the drawing.

The fence post is provided with a concrete base 22 adapted to be embedded in the ground, the cement or other plastic material constituting the base 22 being reinforced and strengthened by a spirally disposed wire 23 wrapped around the base of the post and bearing against the reinforcing ribs 8 and against the adjacent longitudinal edges of said post, as shown.

In operation, the cap 18 is removed and the line wires seated in the recesses 9, after which the locking rod 14 is placed in position with its hooked end 15 engaging the seating recess 16, thus locking the line wires 10 against accidental displacement. The cap 18 is then positioned over the upper end 20 of the fence post with the recess 21 in position to receive the hook 15 of the locking rod, said cap being retained in position on the post by inserting the cotter pin or fastening device 20 through the registering 25 openings in the extension 17 and cap 18, as before stated.

The cap 18 is preferably provided with a knob or finger piece 24 to facilitate placing the cap on or removing said cap from 30 the post.

It will here be noted that the fastening devices 7 serve the dual function of retaining the overlapped ends of the casing sections

in assembled position and also serve to fasten the reinforcing plate to said casing. 35

Having thus described the invention, what is claimed as new is:

1. A post comprising a hollow metallic body portion having exterior angularly disposed ribs gradually increasing in width 40 from the top to the bottom of the post, and a flat reinforcing plate disposed at right angles to the ribs and housed within the body of the post, the upper end of the reinforcing plate being reduced and projected 45 vertically above the top of the post to form a support for a cap.

2. A post comprising a hollow metallic body portion, a reinforcing plate housed within the body portion and having its upper end reduced and projected vertically above the top of the post, a cap having a socket therein for the reception of the reduced end of the reinforcing plate, there being registering transverse openings 55 formed in the cap and reduced end of the plate, and a fastening device extending through said openings for securing the cap in position on the post.

In testimony whereof, I affix my signature 60 in presence of two witnesses.

JOSEPH HUBER. [L.S.].
